(57) **CLAIM**

The ornamental design for an automobile as shown and described.

DESCRIPTION

1. Automobile

1.1 : Front

1.2 : Back

1.3 : Left

1.4 : Right

1.5 : Top

1.6 : Perspective

1.7 : Perspective

The characteristics of the design for which protection is sought include the shape and configuration of the automobile; the bottom view is omitted since the automobile is a heavyweight structure and forms no part of the claimed design.
